UNITED STATES PATENT OFFICE.

DONALD H. REEVES, OF DAYTON, OHIO.

ELECTRICALLY-ACTUATED PUMP.

1,346,555.

Specification of Letters Patent. Patented July 13, 1920.

Application filed November 29, 1918. Serial No. 264,650.

To all whom it may concern:

Be it known that I, DONALD H. REEVES, a citizen of the United States, residing at Dayton, in the county of Montgomery and State of Ohio, have invented a new and useful Electrically-Actuated Pump, of which the following is a specification.

My invention relates to pumps adapted to be placed in the fuel line leading from the tank to the carburetor of a hydro-carbon motor, its prime purpose being to supply fuel to the carburetor under pressure. In its present embodiment it is particularly adapted to use on automobiles, aero planes and the like, and is arranged to start automatically when the pressure in the line drops below a given point and stop when the pressure rises to said point. It is electrically operated and the small quantity of energy required may be obtained from the battery of the ignition system. While quite capable of sustaining the entire burden of maintaining the pressure in the line, it is well adapted to act as an auxiliary whose duty it is to operate only when the major source of pressure is not in operation. For example, in an automobile, where the line pressure is maintained by a pump driven by the motor it is necessary to have some means for building up the pressure before the motor starts; this is commonly done with a hand pump, and my device is adapted to take the place of the hand pump. Connected in the fuel line, with its electrical energy derived from the ignition battery, it can be connected in the ignition circuit so that when the ignition switch is thrown on the current is also thrown into the pump circuit. In its present embodiment my pump is constructed with an elastic cylinder instead of the ordinary piston pump, so all danger of leakage outside of the fuel line is eliminated. Instead of locating the pump in the fuel line, so that it actually pumps liquid fuel, it may be connected to the fuel tank and used to force air under pressure into the tank.

In the accompanying drawing:

Figure 1 is a sectional elevation of my pump;

Fig. 2 is a sectional view of the switch taken on line 2-2 of Fig. 1;

Fig. 3 is a sectional view of a portion of the electrical switch taken on line 3-3 of Fig. 4;

Fig. 4 is a sectional view of the switch taken on line 4-4 of Fig. 2;

Fig. 5 is a sectional view of a portion of the switch taken on line 5-5 of Fig. 2;

Fig. 6 is a fragmental detail showing the construction of the cylinder; and

Fig. 7 is a diagram of the electrical circuit and connections.

Similar numerals refer to like parts in the several views.

Referring now to Fig. 1, the body 10, which is preferably cylindrical, is counter-bored at its lower end to a considerable depth to receive the bottom 11 which is pressed into place. At the center of the bottom a core 12 is secured by a projection 13 on the core and pressed into a hole in the bottom 11. The core is turned true so as to make a good contact with the bottom 11. At its upper end the core is bored out to form a conical recess 14. At its upper end a plug 15 is screwed into the body 10, this plug having a central upward extension 16. The plug and extension are bored out as at 17 to receive a plunger 18. The lower end of the plunger is conical and complementary to the recess 14. The plunger has a central bore 19 whose function is principally to reduce its weight. A non-magnetic peg 20 rigidly attached to the core 12 extending upward into the bore 19 serves as a guide for the lower end of the plunger. At its upper end the plunger is guided by a non-magnetic ring 21 which is secured in the projection 16.

The body 10, bottom 11, core 12, plug 15, and extension 16, are made of soft iron and constitute a double pole magnet, and the plunger 18 acts as an armature for the magnet. A coil 22 of insulated wire is confined in the space formed by the body, bottom, core and plug, the coil thus surrounding the core, so that when a current of electricity is passed through the coil the plunger is attracted and drawn toward the core.

A cylindrical housing 25 slips down over and is secured to the upper end of the body 10, and extending upward a suitable distance this housing is closed by a cover 26. Secured to the inside of this cover and extending downward toward the plug 15, is an expandible cylinder 27. In general form this cylinder is cylindrical, but its wall has a succession of deep corrugations giving it very much the appearance of an accordion.

these corrugations being for the same purpose as the folds of an accordion; namely, to enable the capacity of the cylinder to be increased and diminished. The lower end 5 of the cylinder is closed by a cup shaped head 28, this head having an outwardly extending flange 29 to which the lower end of the cylinder is soldered. The cup part 10 of the head is large enough in diameter to receive the extension 16 and allow plenty of room for the free movement of the cylinder head up and down. The plunger 18 extends upward and is secured to the head 28 at its center, the point of attachment being 15 therefore in the bottom of the cup. A compression spring 30 is confined between the bottom of the cup and the upper end of the extension 16, thereby tending to lift the cup and contract the cylinder, this of course resulting 20 in the plunger being drawn upward with reference to the core 12 and other parts of the magnet.

Extending laterally, then upwardly and again laterally from the flange 29 is an arm 25 35, this arm passing through a roomy aperture in the side of the housing 25. Attached to the housing is a switch base 36 on which is mounted a pair of arms 37 carrying a cylindrical guide rod 38. Loosely mounted 30 on this rod is a metallic sleeve 39 having an annular flange 40 removed a short distance from its upper end. The portion of the sleeve between this flange 40 and its upper end is surrounded by a band 41 composed 35 of insulating material, the diameter of the band being the same as that of the flange. The lower portion of the sleeve is threaded and carries two jam nuts 42. The arm 35 extends into the space between the flange 40 40 and the upper nut 42, so that as the cylinder expands and contracts the sleeve is moved longitudinally on the guide 38. Adjustably secured to the base 36, but insulated therefrom, is a ball holder 43 having two sockets 45 44, each of which contains a ball 45 and a compression spring 46 whereby the ball is pressed against the flange 40 or the band 41, according to the position of the sleeve.

One end of the coil 22 is connected to 50 the binding post 50 and the other end to the ball holder 43. The sleeve 39 is of course connected through its metallic associations to the housing 25 which, for convenience, will be called a ground. Connected to the ball 55 holder 43 is one terminal of a condenser 51, the other terminal thereof being grounded. When the cylinder contracts, the arm 35 moves the sleeve 39 upward to a point where it will contact with the balls 45. Assuming 60 that the binding post 50 is connected to a source of electrical energy, a current will traverse the coil 22, the holder 43, and the balls, and be carried through the flange 40 to the ground. This will energize the

magnet and draw the plunger 18 downward, 6 thus expanding the cylinder. Because of the space between the flange 40 and nuts 42 the cylinder is permitted to expand some distance before the arm 35 engages the nuts, 7 after which the sleeve will be drawn downward until the flange 40 is removed from contact with the balls, the circuit through the coil being thereby broken. The spring 30 is then relied upon to raise the plunger 7 and contract the cylinder, the arm 35 again moving a certain distance before actuating the switch. The stroke of the cylinder may be varied by screwing the nuts 42 toward or away from the flange 40, while the point 8 at which the current is cut off may be varied by moving the ball holder on the base 36. In order to prevent excessive contraction of the cylinder a stop 52, preferably of non-metallic material, such as fiber, is secured in 8 the cover 26, against which the upper end of the plunger impinges. As shown in Figs. 1 and 2, it will be noted that the guide 38 is set obliquely with reference to the axis of the cylinder, the purpose being to impart a rotary movement to the sleeve 39. Because of the angularity of the guide 38, with reference to the line of movement of the plunger 18, there is a lateral movement of the arm 35 with reference to the flange 40 and nuts 42, which lateral movement tends, through the medium of friction, to rotate the sleeve slightly on the guide. While this tendency may not be very pronounced or very uniform, it is sufficient to effect more or less rotary movement of the sleeve.

The cover 26 is fitted with an inlet port 60 which is assumed to be connected to the fuel tank, said port being normally closed by a valve 61. The cover 26 is also provided with an outlet port 62, assumed to be connected to the carburetor, said port being normally covered by a valve 63. These valves may be constructed in any manner suitable for the purpose, and it is deemed unnecessary to describe them in detail.

The operation of the device is almost obvious but may be described as follows: Assuming that the pump is properly connected to the fuel tank and carburetor, but that it has been in disuse and that the pressure in the fuel line is below normal. The cylinder will then be contracted and the parts in the position they occupy in Figs. 1 and 2, the balls being in contact with the metallic part of the switch. Connecting the binding post 50 to a source of energy will immediately energize the magnet and draw the plunger downward, ultimately operating the switch in the manner previously described and cutting off the current. The magnet is required not only to draw fuel from the tank but it must also overcome the tension of the spring 30 which constantly

tends to contract the cylinder. Therefore, as soon as the circuit is broken by the downward motion of the plunger, the spring is allowed to lift the free end of the cylinder, 5 thereby discharging at the port 62 the fluid which was drawn into the cylinder during the downward stroke of the plunger. In like manner the plunger is reciprocated, alternately by magnetic attraction and the 10 tension of the spring, until the pressure in the fuel line is raised to the point where it balances the effective tension of the spring. When this occurs, the spring will be unable 15 to lift the plunger except gradually as the fuel is consumed, and when it is lifted to a sufficient height to bring the flange 40 into contact with the balls the pump will start again and operate as before. In this manner the pressure in the fuel line is automatically 20 maintained practically constant as long as current is supplied at the binding post 50.

While I have used an expandible cylinder in the present embodiment of my invention, this type of pump is not essential to its success as will be perfectly obvious to those skilled in the art; the plunger 18 might readily be connected to the piston of an ordinary reciprocating pump. Moreover, the field of usefulness of my invention is by no 25 means confined to the purposes previously referred to, as it may be put to various other uses. In designing the pump care has been exercised to conserve space and obtain high efficiency. The cup shaped cylinder head 30 contributes very much to the compactness of the device without detracting in any degree from its effectiveness. The magnet is constructed in conformity with the best practice of the day and gives the maximum 35 of power for the current consumed. It is to be understood, however, that I do not confine myself to the particular construction shown, as various modifications may be 40 made without departing from the intent or exceeding the scope of the appended claims.

What I claim is as follows:

1. In combination: a pump comprising an expandible cylinder, one end thereof being secured to a stationary head, the other end being free to move longitudinally and closed 50 by a head; an electro-magnet, an armature connected to the free cylinder head, said armature being attracted and moved by the magnet when the latter is energized, thereby expanding the cylinder, a spring located 55 within the head and constantly tending to contract the cylinder, a switch, and connecting means whereby when the cylinder has been expanded to a given point the switch is opened, and when the cylinder is contracted to a given point the switch is closed.

2. In combination: a pump comprising an accordion like cylinder, one end thereof being secured to a stationary head, the other end being free to move longitudinally and closed by a cup shaped head, an electro-magnet, an armature partly located within and connected to the movable head, said armature being attracted and moved by the magnet when the latter is energized, thereby expanding 60 the cylinder and a compression spring located within the head whereby, when the current is cut off the armature is withdrawn from the magnet and the cylinder contracted.

3. In a pump, the combination of a casing, a collapsible cylinder located within said casing and having one wall thereof fixed therein, a recessed head secured to the free end of the casing and providing a closing 65 end therefor, an electro-magnet, an armature partially located within the recessed head of the cylinder and having a portion thereof secured to said recessed head, said armature being attracted and moved by the magnet 70 when the latter is energized to expand the cylinder, and a spring located within the recessed head and operable to contract the cylinder, substantially as set forth.

DONALD H. REEVES.
